APPARATUS FOR PRODUCING INDICIA
MARKINGS ON WORK SURFACESTheodore Miller, Racine, Wis., assignor to George
Gorton Machine Co., Racine, Wis., a corpora-
tion of Wisconsin

Application April 20, 1945, Serial No. 589,349

15 Claims. (Cl. 33—18)

1

This invention concerns apparatus for producing indicia markings on work surfaces; and the objects and nature of the invention will be made clear by the following explanations of the accompanying drawings illustrating an example mechanical expression or embodiment of the invention from among other forms, modifications and embodiments within the spirit and scope of the invention defined by the appended claims.

This application is a continuation in part of the abandoned application filed by me September 2, 1942, Serial No. 457,088, for Improvements in Apparatus for Producing Indicia Markings on Work Surfaces.

To avoid distortion or marring of work surfaces adjacent to the letters or other identification marks punched or stamped in or on the work surface, and for other reasons, it is now common practice to produce in or on metal work surfaces indicia markings by the electric arc method. By this method, a vibrating consumable electrode is moved laterally over the work surface, and on each rapid short-amplitude oscillatory cycle of the electrode an electric arc is established and extinguished, by making and breaking an electric etching circuit that includes the work surface and the electrode. These electric arcs permanently mark the metal work surfaces by the production therein or thereon of minute pits or craters that do not distort the adjacent portions of the metal surfaces, but merely burn or vaporize the metal to form such pits. The cross dimensions of these marking pits are substantially determined by the cross dimensions of the usually tenuous wire lengths composing the electrodes. Such electric arc etchers are usually carried by an etching head which can be carried or controlled in its lateral movements over the metal work surface by any suitable pantograph mechanism having a stylus to trace a master pattern so that such pattern can be reproduced, usually in scaled relation on the work surface by the electric arcs. Such electric arc etching heads usually include an oscillatory electrode holder and an electromagnetic motor for oscillating said holder with control means. However, to the best of my knowledge and information, these electric arc etchers or markers are not adapted for producing indicia markings on glass, hard or other plastics or other work surfaces that are not composed of good electrical conducting materials.

An object of the instant invention is the production of an improved etcher or marker for the formation or reproduction of permanent in-

2

dicia markings on work surfaces, particularly work surfaces that are not capable of being etched or marked by the hereinbefore described electric arc etchers.

A further object of the invention is the production of an etcher or marker capable of rapidly forming permanent indicia markings in work surfaces by the use of rapidly-oscillatory forcibly-striking impact tools or instruments capable of rapidly producing in such work surface a succession or successions of visible marking minute pits or craters somewhat of the order of the marking pits or craters produced in the metal work surfaces by said electric arc etchers.

15 And another object of the invention is the production of an etcher or marker for operation on work surfaces, comprising a head capable of being carried laterally over the work surface, and supporting vibratory motor means, a percussive 20 or impact tool holder rapidly oscillated by said motor means to forcibly strike the tool against the work surface and retreat the tool therefrom during each oscillation cycle, with the provision of means requiring the tool to strike the work surface with the desired marking force during each oscillatory cycle of such tool.

25 An additional object of the invention is the provision of means interchangeable with certain parts of the electric arc etcher hereinbefore described, whereby such arc etcher, by cutting out or breaking the etching electric circuit thereof, can be converted into an impact etcher or marker capable of producing indicia markings on non-conducting and other work surfaces.

30 A further object of the invention is to provide a mechanical movement or mechanism which, while particularly adapted for embodiment and use in and with an impact etcher of the invention for feeding the tool of the etcher to the work and/or for moving the tool to and from the work surface with the necessary work surface marking force, is also of general utility to form what may be aptly termed a "differential ratchet" type of mechanical movement or mechanism for feeding a member or element progressively in one direction to a predetermined or set limit of motion in that direction, and/or for moving a member or element in opposite directions within predetermined or set end limits; and which mechanical movement or mechanism of the invention is characterized by the fact that it is required or forced to overhaul the member or element being moved thereby in both directions of motion within the predetermined or set end limits or range of motion, but in which a con-

siderably increased application of force is required to cause the mechanism to overhaul the member or element in one direction than the force required to be applied to cause the mechanism to overhaul the member or element in the opposite direction of motion.

With the foregoing and other objects in view, my invention consists in certain novel and advantageous features, structures, combinations, and sub-combinations and arrangements as more fully hereinafter described, and as specified and defined in the hereinafter appearing claims.

Referring to the accompanying drawings, forming a part hereof:

Fig. 1 is a perspective of a head carrying an example embodiment of my instant invention for marking or etching work surfaces by the mechanical action of a rapidly oscillating impact tool, an example impact tool being somewhat diagrammatically indicated, with a portion of its oscillatory holder shown in position elevated from normal operative position with respect to the work surface to be operated on, said head being detached from the pantograph or other mechanism normally employed to carry said head laterally over the normally fixed work during the operation of reproducing indicia markings on the surface of such work.

Fig. 2 is an enlarged front elevation of the oscillatory tool holder and certain associated parts, located within the head of Fig. 1, (the cover plate of said head being removed and part of said head being broken away), certain parts being partially shown, the impact tool or instrument being diagrammatically shown exaggerated in dimensions.

Fig. 3, is a more or less diagrammatical vertical section of the head of Fig. 1, taken approximately in the planes of the line 3—3, Fig. 2.

Fig. 4, is a more or less diagrammatical horizontal section taken approximately in the plane of the line 4—4, Fig. 2.

Fig. 5 is an enlarged detail vertical section of the insulating block or disk on the oscillatory member or arm that oscillates the tool holder, the upper portion of the upstanding lever arm of the tool holder being shown in side elevation.

Fig. 6 is a more or less detail diagrammatical view of certain parts, showing in part any suitable circuit for operating the electromagnetic motor means.

Fig. 7, is a detail perspective somewhat diagrammatical view of the tool holder and certain associated parts, certain parts being partially broken away.

In illustrating an example embodiment of my instant invention, I happen to disclose certain operating and other parts of an electric arc etcher of a construction on the market and in commercial operation, without intending to so limit all features of my invention.

The instant etcher or marker comprises a suitable support that carries the working parts. If so desired, this support can take the form of an attachment or accessory for a machine tool having a work table to which the work can be fixed, preferably, with its surface area to which the indicia markings are to be applied, in a horizontal position or plane. This machine tool usually provides a cutter head, carrying a rotary cutter spindle and its cutter, operatively arranged above and perpendicular to the work surface. Such cutter head is usually universally movable laterally or in a horizontal plane over the work surface through the medium of a hand

operated and controlled pantograph mechanism having a stylus for tracing a fixedly located master pattern of the indicia design or markings to be reproduced on the work surface, usually in reduced scaled relation.

Where the etcher or marker is to be employed as an attachment for such machine tool, although I do not wish to so limit all features of my invention, said support can take the form of a head, 10 for example, a supporting box 1, having a rigid upstanding stud-like shank 2, with certain parts of the work surface marking mechanism in said head, depending therefrom into operative position or relation with respect to the work surface located below the head.

This work surface marking accessory or attachment is operatively secured to the machine cutter head, after the cutter spindle has been temporarily removed therefrom, by inserting the shank 2, in the cutter head and rigidly and removably clamping the same thereto, preferably, with the longitudinal axis of the impact or percussive tool 3, of the marking head in alinement with the longitudinal axis of the machine cutter head.

In this particular example embodiment, the head 1, is in the form of a supporting box or housing having an open side normally closed by a removable vertical cover plate 4, secured by suitable removable fastenings. This cover plate is formed at its lower portion with a vertical slot 4a, through which the lateral arm 5, of a suitable oscillatory tool holder projects to bring the tool 3, normally rigid with and depending from said arm, into operative relation to the work surface.

In this particular example, the oscillatory tool holder takes the form of a bell crank lever rotatably oscillatory on a transverse axial or fulcrum line 7, which in this example can be horizontal or parallel with the work surface w. This bell crank holder comprises the stiff lateral tool-carrying arm 5, and the stiff upstanding lever arm 10, both rigid with respect to each other and radiating from said fulcrum line substantially at 90°. The tool-carrying arm 5, is normally substantially parallel with the work surface, and the tool 3, is located on said arm at a point radially remote from said fulcrum line, and fixedly secured to the arm with the longitudinal axis of the tool perpendicular to the longitudinal axis of the arm, and also substantially perpendicular to the work surface. The tool depends from the arm toward said work surface, and substantially maintains its position perpendicular to said surface throughout its longitudinal oscillations in striking and retreating from said surface.

The tool 3, is preferably replaceably and removably fixed to its oscillatory holder in any suitable manner or by any suitable means. For example, the free end of the arm 5, of the tool holder is provided with a tubular socket 5a, extending transversely therethrough to longitudinally and slidably receive the upper end portion 65 of the shank of the tool 3, and a radial headed clamping screw 5b, is provided for removably locking said tool in said socket against relative lateral and longitudinal movements with respect to arm 5.

The tool 3, is of any suitable structure, formation, and/or material that will satisfactorily perform the functions required; namely, by mechanical striking, impact, percussive or cutting action to produce in the work surface the desired permanent visible indicia markings, preferably, com-

posed of minute crater-like pits, indentations, or craters, say, in diameter and depth substantially of the order of the pits or craters produced by the electric arc etching method.

The tool 3, can consist of a straight small-diameter wire-length, rod, or shank that is stiff or rigid against objectionable lateral buckling or deflection under the endwise impact blows to which it is subjected in action.

The lower or working end of the impact tool 3, provides a rigid strong longitudinal hard sharp or fine puncturing or indenting point 3a, that is in longitudinal alignment with the axis of tool 3. This pointed working end 3a, of the tool can be formed by reducing the end of a hard steel tool 3, to a longitudinally conical or tapered sharp point, or the working end of the tool can be rigidly provided with a diamond tapered to a longitudinal sharp point, or any other hard precious stone or other suitable material can be rigidly secured to the tool 3, to form its working point.

These tools are particularly intended to mark work surfaces of electrical non-conducting materials, such as various hard plastics, hard laminated materials, glass, vitrified and enameled surfaces, etc., although the invention is not so restricted. In some cases the character of the surface to be operated on will determine the character and material of the working point of the impact tool to be employed.

The fulcrum line on which the hereinbefore mentioned example tool holder is rotatably oscillatory, is established by the longitudinal axis of a cross head 5c, 7, 7, forming a rigid part of the holder 5, 10. This cross head includes the two fixed stiff longitudinally aligned opposite-end shafts 7, having end heads 7a, slidably confined to parallel laterally-spaced fixed vertical guide rods 8, between which the cross head is arranged and by which the tool holder is confined against objectionable relative lateral movements or looseness, and is held to rotatable oscillations in a fixed plane perpendicular to the work surface. The end heads 7a, 7a, rigid with the aligned end shafts 7, are preferably flattened to form one an eye and the other a fork to embrace and straddle the guide rods 8, respectively, to facilitate assembly and disassembly of the holder and rods. (See Fig. 7, in particular.) These end heads 7a, 7a, loosely embrace and straddle the guide rods 8, that is, each head 7a fits the respective guide rod 8 on which it is received and mounted, with a slight clearance, so that, the heads 7a, 7a, are capable of limited oscillation on and relative to the rods 8, as the holder rotatably oscillates on its axis 7, 7, 5c, with respect to said guide rods 8.

Any suitable vibratory motor means, can be mounted in and carried by the head 1, for rotatably oscillating the tool holder 5, 10, 5c, on its transverse fulcrum line to rapidly strike the tool against the work surface and lift the same therefrom on each oscillatory cycle.

In the instant example embodiment, I show electromagnetic motor means for thus oscillating the tool holder, comprising an upright metal motor block 11, fixed in the head 1, behind the oscillatory tool holder 5, 10, and carrying a forwardly extending core 15, exposed at the elevated front portion of the block, and the electromagnetic coil 14, for said core, with alternating current electric power source 14a, for rapidly oscillating the motor armature. In this particular example, the motor armature 16, 21, is arranged in operative relation to and in front of the core 15, and behind the tool holder 5, 10, and is removably fixed by machine screws 21a, to the upper end of a

straight flat relatively wide upstanding armature spring 17, at its lower end removably fixed to and spaced forwardly from the front lower portion of block 11, by plates 18, and 19, and suitable removable clamping means 17a, extending through said plates and the upstanding spring 17 and into the block 11.

The armature 16, 21, is fixed to the otherwise free upper end of the oscillatory spring 17, which throughout its oscillations can be maintained substantially parallel with the correspondingly oscillating upstanding lever arm 10, of the tool holder. Spring 17, in this example, is located between said holder arm 10, and the magnet core 15, and its motor block 11. The free upper end of spring 17, to which the armature 16, 21, is fixed, under the influence of the magnetic field when the power current is flowing through the coil 14, rapidly oscillates toward and from the magnet core 15, on preferably short amplitude oscillatory cycles of high frequency, say, of the order of one hundred twenty (120) per second, and having an amplitude suitable for work surface marking purposes, say, of the order of .013", although I do not wish to so limit the invention.

The oscillatory armature 16, 21, is operatively coupled to the upper portion of the tool holder lever arm 10, by any suitable means to oscillate said arm in substantial synchronism with the spring 17, and consequently oscillate the tool holder on its transverse fulcrum axial line, to carry the tool 3, longitudinally against and from the work surface while said tool is maintained substantially perpendicular to said surface.

For example, the armature plate 21, provides a rigid arm or member 9, fixed thereto and extending horizontally and forwardly therefrom in a plane substantially perpendicular to the plane of the armature. The member 9 projects forwardly beyond and intersects the longitudinal axial line of the tool holder lever arm 10, and this member 9 provides a bore extending vertically therethrough intermediate the length and width of member 9, through which said arm 10 vertically extends, and by which it is confined to move forwardly and rearwardly with the reciprocating or oscillating member 9. With this example embodiment, the forwardly projecting metal member 9, is formed with an enlarged intermediate hole or opening extending vertically therethrough, and a relatively thick block or disk 9b, of hard insulating material, is fixed on the top of member 9 with a rigid central depending reduced nipple depending through and filling said enlarged hole or opening through said member 9.

The bore for holder lever arm 10, extends vertically and usually centrally through said disk 9b, and its depending nipple in the hole or opening in member 9, and this bore has an internal diameter greater than the external diameter of holder arm 10, to thereby permit relative rocking movements of the arm 10 within said bore. In order to provide a metal bearing wear and contact surface within said bore for the arm 10, a relatively short metal bushing 9a, is concentrically fixed in said bore, in this instance, if so desired, in the lower end thereof, and this bushing 9a has an internal diameter greater than the external diameter of the holder arm 10. In the specific example hereof, it so happens, that the lower portion or length of the bore through the block or disk 9b is formed of enlarged internal diameter to receive the bushing 9a, with the bushing having an internal diameter substantially

the same as the diameter of the upper portion or length of the bore through block or disk 9b, (see Fig. 5). This bushing 9a provides an internal, rigid, annular concentric flange, in this instance at and around the upper inner end of the bushing, which flange provides a thin circular or annular bearing edge 9c having a reduced internal diameter relative to the internal diameter of the bushing 9a and the bore in block 9b, so as to more or less snugly receive and surround the usually cylindrical smooth exterior surface of the arm 10. The relatively thin circular bearing edge 9c provided by the bushing 9a, forms and constitutes the bearing surface of the member 9 that contacts the arm 10 in order to confine said arm 10 to member 9, against objectionable looseness and possibility of chatter.

In the particular example illustrated, the tool holder 5, 10, and its attached parts, are suitably electrically insulated from the tool holder actuating member 9, and from the motor block 11, and the guide rods 8, fixed to motor block 11 by brackets 12, and from other parts that may be electrically included in the electric power circuit that actuates the electromagnetic motor.

In this particular embodiment of the invention, the electromagnetic vibratory motor, includes a longitudinally elongated armature spring 17 fixed at its lower end and at its upper end fixedly carrying the armature from which member 9 projects forwardly substantially horizontally. Hence, the armature and member 9 will oscillate in an arcuate path from the center of oscillation located above the clamping plates securing the lower end of spring 17. For example, in this instance, this center of oscillation is located intermediate and approximately midway between the upper ends of the clamping plates 18, 19, which secure the lower end of the spring 17 to the motor block 11, and the lower end or side of the armature 16, 21, fixed on the spring 17. However, it is to be understood that the particular location of the center of oscillation of the armature and member 9, in this particular example of an embodiment of my invention, is not a critical location for other embodiments, forms and arrangements. This arcuate path of oscillation will dip or curve downwardly at the forward portion thereof and thus cause the actuating arm or member 9 at the forward portion of its forward stroke to move down with respect to the tool holder arm 10.

In this particular embodiment, the vertical armature spring 17, when at rest, as when the electromagnetic motor is not operating, is not under tension but assumes its normal straight, flat vertical form holding armature 16, 21, and hence the member 9 and the holder arm 10, at their respective positions of rest intermediate their respective end points of forward and rearward oscillations. At its inactive position or position of rest, the holder arm 10 is preferably vertical and parallel with the vertical upstanding spring 17, and the tool 3 is maintained substantially perpendicular to the surface of the work w (see Fig. 3). The arrangement of the spring 17 with the armature 16, 21, and the motor core 15, is in this specific example, such that the distance of the rearward movement of the member 9 and the parts associated therewith, is greater than the distance of the forward movement thereof from their inactive positions or positions of rest, although it is to be understood, that such condition is not essential to or a critical factor of my invention, as, if desired, for example, the distance of the forward movement and the distance

of the rear movement of the member 9 may be equal and the same, or, if the conditions of any particular embodiment or installation, such as the degree of flexibility or stiffness of the armature spring, make it of advantage or expedient, the distance of forward movement of the member 9 may be less than the distance of rear movement thereof.

The rotatably oscillatory tool holder organization, and its actuating member 9, as so far described, can be employed for electric arc etching where an etching circuit is provided, and on each oscillation the electrode merely more or less lightly touches or contacts the work surface to establish and then extinguish the work surface burning arc, as the mere slight contact between the electrode and work surface is solely for the purpose of establishing such work surface burning arc. A forceful blow of the electrode against the work surface is not only unnecessary but is objectionable in electric arc etching, particularly because of the tenuous character of the electrode wires employed. Thus, when the organization as hereinbefore described, is employed for arc etching, the holder lever arm 10, is free to cushion the contact of the work surface by relative vertical, minimum friction, sliding movements longitudinally of the arm between member 9 and arm 10. In other words, the arm 10 is freely slidable through the member 9, particularly when the arm 9 and the electric arc etching electrode holder are operated at high speed with said holder under constant gravity urge to bodily feed down toward the work surface with respect to actuating member 9. Under such conditions in arc etching, when the smooth surfaced holder arm 10, is oscillated at high speed by the actuating member 9, there results intermittent reduction of the frictional pressure between the smooth surface of arm 10, and the annular thin bearing surface 9c, of the member 9, with bodily downward gravity feeding of the holder and its upright arm 10 through the member 9. This is satisfactory for electric arc etching but not for mechanical impact tool etching.

I have discovered that if a proper impact marking tool is substituted in the arm 5, of the oscillatory holder 5, 10, for the electrode carried by such holder for arc etching, and if added features are cooperatively associated with both the lever arm 10 and the actuating member 9, to resist upward movements longitudinally of arm 10, between member 9 and arm 10, during each stroke of holder arm 5, and its tool 3, toward and against the work surface, the tool will strike the work surface under sufficient force and pressure to successfully carry on mechanical impact marking of such work surfaces when of non-electrical conducting and certain other materials.

My instant invention contemplates the use of any suitable means that, while permitting relative longitudinal movement of the oscillatory holder arm 10 relative to its actuating member 9 away from and toward the work surface, will automatically cause greater resistance to be offered to such movement of the holder arm 10 away from the work surface, than will be offered to movement of the holder arm 10 relative to the actuating member 9 in the opposite or reverse direction, that is, toward the work surface, during each tool holder oscillation from and toward the work surface. In other words, the means contemplated and provided by my invention for associating the oscillatory holder arm 10 with the actuating member 9 for oscillating the same, is such as will per-

mit movements of the holder arm 10 and its actuating member 9 relative to each other, but will require the application of a greater force to cause longitudinal movement of arm 10 relative to actuating member 9 away from the work surface than the force required to be applied to cause movement of the arm 10 relative to the member 9 toward the work surface. Thus, an operative association of the actuating arm or member 9 and the tool holder arm 10 is provided by which member 9 and arm 10 are movable relative to each other, but in which resistance is offered to such movements. The magnitude of such resistance is, as explained above, such that greater resistance is offered to movement of the tool holder arm 10 away from the work than is offered to movement thereof toward the work. In this manner an amount of kinetic energy from the total kinetic energy stored in the armature spring system, is transmitted to the tool holder arm 10 during oscillation of the tool holder toward the work surface, and hence, the required amount of kinetic energy to be transmitted to the tool holder arm 10 during oscillation of the tool holder toward the work surface, necessary to force tool 3 to strike the work surface during such oscillation with sufficient force or impact to cause the mechanical impact marking of such surface, can be determined by providing a resistance to movement of the tool holder arm 10 away from the work surface, of a required predetermined magnitude.

For instance, various camming means can be cooperatively associated with the tool-holder arm 10 and the actuating member 9 for such arm, to successfully solve the above mentioned problem and attain the desired results. As one example embodiment from among other camming means that can be employed, I provide the upstanding lever arm 10, with a longitudinal smooth flat wedging or camming surface *a*, the exterior smooth surface of the arm 10 being otherwise preferably cylindrical. This surface *a*, extends longitudinally throughout and beyond that portion of the length of arm 10, that passes through the member 9, or that will be located in said member during the marking operations. This flat *a*, takes the form of a plane arranged longitudinally of arm 10, and intersecting the same at a wedging or camming angle to the longitudinal axis thereof. Thus, the wedging flat *a* is inclined from a lower intermediate surface point in the length of arm 10, and extends longitudinally and inwardly thereof toward its longitudinal axis to its upper end. This flat *a*, is preferably located at the front side of the arm 10, that is, the advancing side of said arm when said arm and the tool holder are moved forwardly to strike the tool on the work surface. The straight, flat, inclined plane surface *a*, longitudinally increases in depth toward the upper or top end of arm 10, and thereby cooperating force applied radially of said arm 10 from the arm 9, against said cam surface *a*, resists longitudinal upward relative movement, of said arm 10, under certain conditions, with respect to the actuating member 9, until such resistance is overcome by the application of an opposing force of sufficient magnitude. The cooperating force applied radially of said arm 10 from the actuating member 9, against cam surface *a*, is preferably of sufficient magnitude to prevent the arm 10 from moving or feeding longitudinally downwardly under the force of gravity acting thereon, while the actuating member 9 and the arm 10 carried thereby are at rest, due to frictional forces which are established acting on the arm 10 to re-

sist and overcome the gravity urge thereon, but due to the formation and arrangement of the flat, inclined plane surface *a*, the force required to be applied to relatively longitudinally move the tool holder arm 10 relative to actuating member 9 toward the work surface, is considerably less than the force required to be applied to move holder arm 10 in the opposite direction, that is, in a direction away from the work surface.

10 In this particular example, said radial force carried by the actuated member 9 is slideably applied to the inclined cam surface *a*, through the medium of a longitudinally slideable spring pressed plunger *b*, arranged radially of the tool holder arm 10, and carried by the block or disk 9b rigid with actuating arm 9, and longitudinally slideable through said block, and preferably provided with a smooth or rounded inner contact end constantly held under spring pressure in camming, sliding and frictional engagement with the longitudinally inclined cam surface *a* of arm 10.

25 The plunger *b*, is preferably longitudinally slideable in and confined by a fixed bushing *c*, extending radially through the block 9b, from the vertical bore thereof to a point at the exterior of said block. This radial plunger is preferably located in a horizontal plane above the horizontal plane of the annular bearing edge 9c that contacts holder arm 10.

30 Any suitable spring means can be provided to constantly maintain the longitudinally slideable plunger *b*, under the required yielding inward pressure against the cam surface *a*, of holder arm 10. For example, from among other spring means that can be employed, I show spring *d*, exteriorly coiled around block 9b and at one end fixed there-

35 to with its active free end *d*', under constant tension to spring inwardly toward the block surface. This active spring end *d*' traverses the outer end of plunger *b*, to constantly tend to force said plunger inwardly against cam surface *a*. The projecting outer end of bushing *c*, can be slotted to guide and maintain spring end *d*' in constant operative contact with the outer end of the plunger.

40 The plunger *b*, is located in the vertical plane that includes the longitudinal axis of holder arm 10, which is also the vertical plane in which said arm 10, oscillates forwardly and rearwardly. As the longitudinal cam surface *a*, of the holder arm 10, is located at the front or advancing side of holder arm 10, when the holder is on its forward oscillation carrying the tool 3 down to strike the work surface, the rearwardly, spring pressed plunger *b*, is also located in said front side of arm 10 exerting rearward pressure against cam surface *a*, of said arm.

45 The relative arrangement of the arm 10, and its longitudinal cam surface *a*, with respect to the transversely oscillating actuating arm or member 9 and its plunger *b*, are such that during tool holder oscillation, the holder arm 10, is under the constant radially applied forces exerted thereon by the plunger *b* to establish friction forces between the surface 9c of the actuating arm or member 9 and the inner end of the plunger *b* and adjacent cylindrical or curved surface of the holder arm 10, and between the inner end of the plunger *b* and the inclined flat surface *a* of arm 10, so that, upward longitudinal movement of arm 10 is resisted to a greater degree than downward longitudinal movement thereof, through and with respect to the actuating arm or member 9.

50 Assuming that the motor is at rest with the

spring 17 and its armature and the tool holder and its tool 3, in the positions as shown in Figs. 3 and 6, then, upon energizing the motor, the armature 16 is pulled rearwardly toward the core 15 with relatively great acceleration and due to the inertia in the tool holder, the bushing 9a and member 9 slip upwardly a short distance on or overtake arm 10, that is, in effect, the arm 10 slips downwardly a short distance relatively to the bushing 9a and the actuating arm or member 9, before the tool holder can be accelerated to the speed of upward and rearward movement of the bushing 9a and the actuation arm or member 9. However, as soon as the tool holder has attained the speed of movement of the bushing 9a of actuating arm 9 as such arm and the bushing move through their upward and rearward path of oscillation, the holder arm 10 is picked up by and proceeds at the same rate of movement as and moves upwardly and rearwardly with, actuating arm or member 9. At the same time the end heads 1a, 1a, of the shafts 7 of the tool holder, are moved vertically on rods 8, respectively, and the point 3a of the tool 3 has the resulting compound motion applied thereto so that the tool point 3a partakes of such motion.

When the actuating arm or member 9, and the tool holder including the tool holder arm 10 and tool 3, have reached the end limit of their rearward oscillation or movement, the tool holder and tool 3 are at their limit of upward and rearward movement, and core 15 is deenergized and the deflected armature spring 17 is released, so that, the energy stored therein will oscillate or spring the spring and the armature forwardly away from the core 15, thus reversing the direction of movement of the armature and of the member 9 and tool holder associated therewith. Upon the reversal of the direction of motion of the armature, by the spring 17, as aforesaid, the member 9 and the tool holder arm 10 and tool holder 5, are accelerated in a direction forwardly and downwardly from their respective end limits of upward and rearward movement, by the armature spring. And again the inertia of the tool holder arm 10 and the tool holder carried thereby, functions to cause the bushing 9a of the actuating arm or member 9 to slip downwardly on and overtake the holder arm 10, the holder arm 10 in effect slipping upwardly through the bushing 9a, but while the inertia of the tool holder assembly is the same on this forward stroke as on a rearward stroke, nevertheless, the bushing 9a and actuating arm or member 9 will slip downwardly on or overtake the arm 10 for a lesser distance or extent than the distance that the bushing 9a and arm 9 slips upwardly on and overtake arm 10 on the rearward stroke or oscillation.

This difference between the distance the bushing 9a and arm 9 slip upwardly on or overtake holder arm 10 on the rearward and upward oscillation stroke and the distance which the bushing 9a and arm 9 slip downwardly on or overtake the arm 10 on the forward and downward oscillation stroke, notwithstanding the fact that the inertia of arm 10 and its associated tool holder is the same on both forward and rearward oscillation stroke, is due to the fact that the arrangement of the inclined surface or flat a and the presser pin b which engages such surface, is such, that the pressure exerted by presser pin b upon the inclined surface a of arm 10 requires a greater force to move arm 9 and bushing 9a downwardly on and relative to arm 10 than is required to move the bushing 9a and arm 9 upwardly rela-

tive to the arm 10. As the armature 16, with the tool holder actuating arm or member 9 and tool holder assembly carried thereby, move forwardly and downwardly through the forward oscillation stroke, the end heads 1a, 1a, of the tool holder shafts 7, are also simultaneously moved downwardly on the rods 8, respectively, and the tool point 3a of the tool 3 carried by the tool holder again has the compound motion imparted thereto, so that the tool point 3a partakes of such compound motion.

Thus, a yielding association or junction is provided between the holder arm 10 and the bushing 9a in which said arm is received and mounted on the actuating arm or member 9, of a character to permit upward motion of the arm 10 through and relative to the bushing 9a while the actuating arm or member 9 is still in its forward and downward oscillation for impact striking of the tool 3 on the work surface 2. With the yielding junction between the arm 10 and the bushing 9a, if the arm 10 has on the rearward oscillation stroke of the actuating arm or member 9, dropped downwardly a distance greater than the distance necessary in order to compensate for wear of the tool point 3a or for undulations in the work surface, then, of course, the tool point 3a will on its forward oscillation stroke contact the work surface before the member 9 has completed its forward stroke. Under these conditions the upwardly acting forces imposed on the arm 10 by this premature engagement of the tool point 3a with the work surface, will overcome the forces acting on the arm 10 to resist upward movement thereof through and relative to bushing 9a and to the actuating arm 9, so that arm 10 will be forced longitudinally upwardly through bushing 9a the required distance to permit actuating arm 9 to complete its forward oscillation.

But while this junction between the arm 10 and the bushing 9a must be yielding, it must also be capable of transmitting the desired amount of kinetic energy from the armature spring system to the tool holder, and the amount of energy so transmitted is primarily dependent upon the pressure exerted on the inclined plane or flat a by the presser pin b , and the inclination of the inclined plane or flat a relative to the longitudinal axis of arm 10, and the coefficient of friction between the coacting parts. The cooperating action of the camming device consisting of the flat inclined surface a on the arm 10 and the presser pin b carried by the bushing 9b, during operation of the oscillating or actuating arm or member 9, while the tool holder assembly is thereby oscillated on and about its fulcrum line 7, automatically, in effect yieldingly locks or maintains the tool holder arm 10, against upward longitudinal movement through the bushing 9b on the oscillating actuating arm or member 9, during each forward stroke of the tool holder that carries the tool point 3c of the tool 3 into striking contact with the work surface. Each surface striking stroke of the tool 3, is hence, forcibly made under the required downward pressure or force to mechanically produce the desired mark by impact or percussive action on the work surface.

By varying the tension of spring d and consequently the lateral camming or wedging pressure applied to the longitudinal upwardly and rearwardly inclined plane cam surface a of the tool holder lever arm 10, through the medium of the spring pressed plunger b , and by varying the angular relationship between the inclined cam

surface a , and the longitudinal axis of the lever arm 10 , the downward pressure, or downwardly acting force, on, and hence the striking force of, the tool 3 , on the work surface may be varied over a wide range within the limits of the particular organization.

In the particular example illustrated the oscillatory tool holder $5, 10$ and its tool 3 , are normally held in an elevated inoperative position with respect to the work surface w , by any suitable forwardly spring pressed plunger 25 , having a radially projecting lifting toe $25b$ located below a lifting arm 26 , rigid with the tool holder lever arm 10 and projecting therefrom into the path of vertical movement of the toe $25b$. The spring elevated plunger 25 (see Fig. 1) constantly tends to raise holder $5, 10$ with respect to actuating arm 9 , and guides 8 , and to maintain said holder in elevated position in inoperative relation to the work surface. When it is desired to produce indicia marking on the work surface, the power circuit is closed through the electromagnetic motor to start the tool holder oscillation, and thereupon the machine operator by application of downward pressure on the exposed head or button $25a$ of plunger 25 , forces said plunger to its limits of downward movement against the upward pressure of its lifting spring 28 , and thereby permits the then oscillating tool holder $5, 10$ to be progressively fed downwardly until stopped by the engagement of tool 3 with the work surface. This progressive downward feeding of the tool holder results from the fact that on each rearward and upward stroke or oscillation of the actuating arm 9 , such actuating arm overhauls or slips upwardly on the tool holder carrying arm 10 a greater distance than the said arm 9 overhauls or slips downwardly on the tool holder arm 10 on each forward and downward oscillation stroke thereof. When the tool holder reaches a position at which the rapidly vibrating tool 3 strikes the work surface w , the continued downward bodily movement of the tool holder as a unit is stopped by the engagement of tool 3 with the work surface, and thereafter the tool holder is maintained as a unit in such a position where it then continues to rotatably and vertically oscillate relative to the work surface w with the point $3a$ of the tool 3 rapidly successively striking the work surface with sufficient force or impact to form the desired markings on the work surface as the tool is motioned laterally relative to the work surface. As above explained, the tool holder and the tool 3 are under constant urge toward the work surface, so that, tool point wear or undulations of the work surface will be automatically compensated for as a result of the relative arrangement and association between the tool holder arm 10 and the bushing $9a$ carried by the oscillating actuating arm 9 , through the medium of the camming means provided by the inclined flat cam surface a on the arm 10 engaged by the spring loaded presser pin b .

Thus, during a normal marking operation, the operator holds the plunger 25 depressed, but as this plunger 25 is under constant spring pressure to return to elevated position, when the operator completes the marking operation, the head or button 25 may be released and the lifting device will thereupon immediately lift the holder $5, 10$ from operative position. However, it is not deemed necessary to fully illustrate this lifting device herein, as it forms no part of my invention, and I do not wish to limit my invention to inclusion therein or use therewith.

In Fig. 2 of the drawings, I happen to show vertical smooth wire lengths 23 depending in front of the cylindrical end shafts 7 , and constantly exercising more or less rearward lateral pressure against said shafts 7 , to yieldingly hold the shaft ends $1a$ laterally against the guides 8 , respectively, so as to avoid chatter when the tool holder is operating at high speed. These spring lengths 23 can be secured at their upper ends with the rearwardly pressing lower ends free and slideably engaging the shafts 7 , respectively. However, my instant invention is not limited to the employment of such lateral pressure means as such means are not essential or necessary. For example, I have discovered that when the spring d exerts a force of sufficient magnitude to engage the pin b under a considerable pressure against the cam surface a of the tool holder arm 10 , that the spring wire lengths or fingers 23 need not be used and are not necessary in order to prevent chatter.

While the force exerted by the spring wire lengths or fingers 23 , when such fingers are arranged as disclosed in the example herein illustrated, is applied primarily for the purpose of preventing lateral motion of the shaft ends $1a$ relative to the rods 8 on which they are mounted, so as to prevent chatter, attention is directed to the fact that my invention contemplates and includes the use of these fingers 23 to apply downward acting forces to the tool holder, that is, in a direction toward the work surface. Such contemplated function for the fingers 23 is accomplished in the present instance by inclining the upper end lengths of the fingers 23 rearwardly above shafts 7 , relative to the vertical plane traversed by these shafts, so that, these spring fingers then yieldingly press downwardly upon shafts 7 , as will be readily understood.

In the particular example illustrated, without intending to so limit my instant invention, the tool holder is confined and guided to straight-line bodily vertical movements by smooth surface depending rods 8 , rigid with and depending from brackets 12 projecting forwardly from the motor block 11 , and removably clamped thereto by removable machine screws $12a$ or other suitable means, for ease in assembly and disassembly. Also if so desired, the lower end of one or both of said guides 8 , can be provided with a removable stop $6a$, for ease in removing and applying the tool holder to and from said guides 8 .

As hereinbefore stated, it is desirable to electrically insulate the tool holder and its impact tool 3 , from the power circuit that operates the electromagnetic vibratory motor. Hence, should it be desirable to form the block $9b$, on the vibratory holder actuating arm 9 , of metal or electrical conducting material, the holder lever arm 10 , can be composed of two axially aligned metal rods insulated from each other and rigidly connected by a coupling, composed of insulating material n and an exterior rigid tube or sheathing. (See Figs. 2 and 3.)

The tool holder can also be insulated from the brackets 12 , and guide rods 8 , by insulation m , (see Fig. 7) between each shaft 7 , and the cross head $5c$.

Where the block $9b$ is composed of electrical insulating material to thereby insulate holder lever arm 10 from member 9 , the arm 10 can be composed of a single rod as shown by Fig. 6. However, I do not intend or wish to limit my instant invention to such specific examples.

It is also a further purpose of this embodiment

ment to permit replacement of the etching electrode by a mechanical etching or engraving tool, such as a diamond or conical shape supported in a suitable shank or other holding means so that indicia or the like may be mechanically inscribed on non-metallic surfaces as glass, plastics, and the like, by means of the short percussion blows of the engraving tool on said surfaces, and without the aid of electric arcs.

Although I do not wish to so limit all features of my instant invention, the specific embodiment shown herein as an example was particularly designed as an interchangeable accessory, applicable to and removable from, a known commercial type of electric arc etcher, to temporarily or otherwise, convert the same for use in producing indicia markings on work surfaces of non-electrical conducting materials by a mechanical impact tool or the like. Obviously, however, my instant invention can be employed in more or less permanent form as a complete machine for producing indicia markings on work surfaces by the mechanical action of any suitable impact or striking tool or instrument.

The instant disclosure shows the example embodiment of my invention included in said commercial electric arc etcher, in place of the electrode holder, the electrode, the etching electrical circuit, and the insulating plug forming the bore of the motor driven oscillatory arm that actuates the electrode holder of said arc etcher.

For instance, the tool holder 5, 10, can be removed by dropping the same down through the block 9b until the eyes 7a are clear of the rods 8, the stop 8a having been removed, or the rods 8, can be detached by removing the screws 12a that secure the brackets 12, to the motor block and then the arm 9, can be removed with the tool holder and its lever arm 10 by removing the screws 21a securing armature block 21 of the armature 21, 16, and its spring can be removed with the tool holder 5, 10 by removing the screws 17a that secure the spring clamping block 18.

By my invention a mechanical movement or mechanism is provided for moving or progressively feeding a member or element in one direction to a predetermined limit of motion for the element or member in that direction, and/or for moving a member or element in opposite directions within predetermined or set end limits. A mechanical movement or mechanism of the invention may be aptly termed a "differential ratchet" mechanism, the term "ratchet" being used in a broad, generic sense for purposes of convenience primarily, and not in its more limited mechanical or specific structural sense. The mechanism functions as a "ratchet," in that, it overhauls the member or element to be moved for a distance before engaging and moving the same in either direction of motion of the member, but is so arranged as to overhaul the member a greater distance in one direction of motion than in the other or opposite direction of motion, with the result that, the element is progressively fed in only one direction of motion. The adaptation or mechanical expression of this mechanical movement of my present invention, as disclosed and described herein, is, of course, primarily adapted for moving or vibrating the impact tool of an impact etcher toward and from the work surface, but it embodies the principles of this mechanical movement of my invention in that, the member 10 which forms the carrying arm for the tool holder is so cooperatively associated with the oscillating actuating member 9, through

the medium of the camming means consisting of the cam surface *a* on member 10 engaged by the pressure pin *b* on member 9, that, as the actuating member 9 is oscillated or reciprocated generally longitudinally of the member 10, it will overhaul or slip along member 10 for a distance during its movement in either direction, due to inertia forces, before frictionally holding and moving the member, but will overhaul member 10 a greater distance in one direction of motion than in the other, with the result that, while the member 10 is alternately moved in opposite directions, that is, oscillated through a fixed path, it will be progressively fed or moved step by step in the direction of motion opposite to that direction of motion or stroke of member 9 during which member 9 overhauls the member 10 for the greater distance.

This "differential ratchet" mechanical movement or mechanism of my present invention is adapted to embodiment in various arrangement and combinations to meet particular operating and use conditions, such for example, as a mechanical movement or mechanism for limiting pressure in rectilinear motions.

The disclosures hereof have been specifically described merely for purposes of explanation and not for purposes of limitation beyond that required by the appended claims, as I realized, as will be evident, that various modifications, variations, changes, adaptation, substitutions and eliminations are possible within the spirit and scope of my invention.

What I claim is:

1. Apparatus for producing permanent indicia markings on work surfaces by the mechanical action of an impact marking instrument; comprising a holder for the impact marking instrument, said holder adapted to fixedly hold said instrument substantially perpendicular to the work surface, said holder being oscillatory to carry said instrument endwise into forceful marking engagement with said surface and to lift said instrument therefrom on each oscillation cycle; vibratory motor means for oscillating said holder including a holder actuating connection, said holder being relatively movable with respect to said connection; and wedging means between said connection and said holder for exerting wedging urge on said holder and said instrument toward the work surface during each surface striking stroke of said instrument to resist relative upward movement of said holder with respect to said connection under the impact of the instrument on the work surface.

2. Apparatus for producing indicia markings on a work surface, comprising a holder; an impact surface marking tool normally rigidly fixed to said holder and depending therefrom toward the work surface substantially perpendicular to said surface, said holder being oscillatory to forcibly endwise strike said tool against said surface and raise the same therefrom on each oscillation cycle; means for oscillating said holder including an oscillatory motor and a holder actuating member oscillatory in a fixed path transversely with respect to the axis of said tool driven by said motor, said holder being relatively rockable and transversely movable with respect to said member during said oscillations; and camming means between said holder and said member.

3. Apparatus for producing indicia markings on a work surface, comprising a holder; a mechanical work surface marking tool normally

rigidly held by said holder for endwise forcefully striking the work surface; said holder being oscillatory to forcefully strike said tool against said surface and lift the same therefrom on each oscillatory cycle; an oscillatory motor operatively and slideably coupled to said holder to oscillate the same and permit relative movements thereof toward and from said surface; and camming means acting on said holder to resist movement of said holder and its tool longitudinally away from said surface during each surface striking stroke of said tool.

4. Apparatus for producing indicia markings on a work surface, comprising a holder; a mechanical work surface marking tool normally rigidly held by said holder for endwise forcefully striking the work surface; said holder being oscillatory to forcefully strike said tool against said surface and lift the same therefrom on each oscillatory cycle; an oscillatory motor; a coupling operatively slideably coupling the motor with the holder for relatively moving the holder toward and from the work surface; camming means acting on said holder to resist movement of said holder and its tool longitudinally away from said surface during each surface striking stroke of said tool, said camming means including a longitudinally inclined camming or wedging surface on said holder, and means on said coupling for applying pressure on and transversely of said wedging surface, said camming means being actuated to exert force on the holder to resist movement of the tool holder and its tool longitudinally away from the work surface with respect to said coupling under the impact of the tool against the work surface.

5. Apparatus for producing indicia markings on a work surface, comprising a holder; a mechanical work surface marking tool normally rigidly held by said holder for endwise forcefully striking the work surface; said holder being oscillatory to forcefully strike said tool against said surface and lift the same therefrom on each oscillatory cycle; an oscillatory motor; a coupling operatively slideably coupling the motor with the holder for relatively moving the holder toward and from the work surface; camming means acting on said holder to resist movement of said holder and its tool longitudinally away from said surface during each surface striking stroke of said tool, said camming means including a longitudinally elongated laterally inclined cam flat or surface provided by said holder, and a spring pressed plunger supported independently of said holder and cooperating with said surface to establish forces to resist movement of said holder in a direction away from said work surface.

6. Apparatus for producing indicia markings on a work surface, comprising a holder; a mechanical work surface marking tool normally rigidly held by said holder for endwise forcefully striking the work surface; said holder being oscillatory to forcefully strike said tool against said surface and lift the same therefrom on each oscillatory cycle; an oscillatory motor; coupling means operatively slideably associating the motor with the holder for relatively moving the holder and its surface marking tool toward and from the work surface; said surface marking tool being stiff against lateral deflection and depending from said holder toward the work surface and being provided with an axially aligned hard sharp surface indenting point; said holder including a longitudinally movable lever arm; and said coupling means providing a holder oscillating mem-

ber vibratory transversely of said arm with said arm operatively confined thereto for relative sliding movements with respect to said member.

7. Apparatus for producing indicia markings on a work surface, comprising a holder; a mechanical work surface marking tool normally rigidly held by said holder for endwise forcefully striking the work surface; said holder being oscillatory to forcefully strike said tool against said surface and lift the same therefrom on each oscillatory cycle; an oscillatory motor; coupling means operatively connecting the motor with the holder for relatively moving the holder and its tool toward and from the work surface; camming means acting on said holder to resist movement of said holder and its tool longitudinally away from said surface during each surface striking stroke of said tool; said coupling means providing for movements of said holder vertically in opposite directions relative to said coupling means; and said camming means acting on said holder to resist movement of said holder and its tool longitudinally from said work surface.

8. Apparatus for producing indicia markings on a work surface, comprising a tool holder rotatably oscillatory on a transverse axis; an impact work surface indenting tool normally fixed to a holder to forcefully strike the work surface and withdraw therefrom during each oscillation cycle of the holder; a holder actuating member oscillating in a fixed path; a vibratory motor for oscillating said member, said holder being coupled to said member in driven relation, said holder being vertically movable with respect to said member during holder oscillations; and means for applying wedging pressure on said holder to resist upward movement of the tool during each stroke of the holder to forcefully strike the tool against the work surface, said means including an upwardly and laterally inclined longitudinal wedging surface provided by the holder, and a plunger carried by said member substantially perpendicular to said wedging surface and spring pressed against said wedging surface.

9. An accessory comprising an oscillatory tool holder having a work surface impact or indenting tool normally fixedly secured thereto, said holder including an actuating lever arm provided with a longitudinal laterally inclined cam or wedging surface; and an actuating member for oscillating said holder, said arm transversely traversing said member for relative longitudinal movements with respect thereto and provided with a plunger spring-pressed against said cam surface to exert wedging urge against said lever arm.

10. Apparatus for producing indicia markings on a work surface by the mechanical action of an impact marking tool; comprising a holder for the impact marking tool, said holder being adapted to fixedly hold said tool substantially perpendicular to the work surface, said holder being mounted for oscillation to carry said tool endwise into forceful marking engagement with said surface and to lift said tool therefrom on each oscillation cycle; means for oscillating said holder; an actuating member operatively connecting said holder with said oscillation means, said holder being relatively movable with respect to said actuating member toward and from the work surface; means engaging said holder adapted to resist movements of the holder in either direction; and said holder and holder

engaging means being constructed and arranged to offer greater resistance to movement of the holder in a direction toward the work surface than to movement of the holder in a direction away from the work surface.

11. Apparatus for producing indicia markings on a work surface by the mechanical action of an impact marking tool, comprising a holder for the impact marking tool, said holder being adapted to fixedly hold said tool substantially perpendicular to the work surface, said holder being mounted for oscillation to carry said tool endwise into forceful marking engagement with said surface and to lift said tool therefrom on each oscillation cycle; means for oscillating said holder; an actuating member operatively connecting said holder with said oscillation means and being adapted to be oscillated by said means to oscillate said holder; said holder being slidably engaged with said oscillatory actuating member and being relatively movable with respect to said actuating member toward and from the work surface; and means constructed and arranged to engage said holder to establish friction forces between said holder and said actuating member acting to establish greater resistance to movements of said holder away from the work surface than to movements of said holder toward the work surface.

12. Apparatus for producing indicia markings on a work surface by the mechanical action of an impact marking tool, comprising a holder for the impact marking tool, said holder being adapted to fixedly hold said tool substantially perpendicular to the work surface, said holder being mounted for oscillation to carry said tool endwise into forceful marking engagement with said surface and to lift said tool therefrom on each oscillation cycle; means for oscillating said holder; an actuating member operatively connecting said holder with said oscillation means and being adapted to be oscillated by said means to oscillate said holder; said holder being slidably engaged with said oscillatory actuating member and being relatively movable with respect to said actuating member toward and from the work surface; and means mounted on and carried by said actuating member and being engaged with said holder to establish friction forces causing greater resistance to movements of said actuating member away from the work surface than to movements thereof toward the work surface.

13. In combination, a member adapted to be progressively fed in one direction, an actuating arm adapted to be oscillated through a fixed path of oscillation, said actuating arm being disposed substantially transversely relative to the path of movement of said member, said member being slidably engaged with said arm for movements relative to and substantially transversely of said arm in opposite directions, means for establishing friction forces between said arm and said member for resisting movements of the member relative to the arm in either direction, and said friction force establishing means, arm and member being arranged and constructed to cause said means to establish friction forces of greater magnitude for resisting movements of said member relative to said arm in the direction of feed than the magnitude of the forces established thereby

resisting movement of said member relative to said arm in the opposite direction.

14. In mechanism for oscillating a member in a fixed path between predetermined end limits of oscillation and for progressively feeding the member in one direction of the path of oscillation, in combination, a member to be oscillated and fed, said member being mounted for oscillation, an actuating arm adapted to be oscillated through a fixed path of oscillation, said actuating arm being disposed substantially transversely relative to the path of movement of said member, said member being slidably engaged with said arm for movements substantially transversely of and relative to said arm in opposite directions, means establishing friction forces acting on said member for resisting movements of the member relative to the arm in either direction; and said means and said member being constructed and relatively arranged to offer greater resistance to movements of said member in the direction in which the member is to be fed than to movements of the member in the opposite direction.

15. Apparatus for producing indicia markings on a work surface by the mechanical action of an impact marking tool; comprising a holder for the impact marking tool, said holder being adapted to fixedly hold said tool substantially perpendicular to the work surface, said holder being oscillatory to carry said tool endwise into forceful marking engagement with the work surface and to lift said tool therefrom on each oscillation; means for oscillating said holder including a holder actuating connection, said holder being relatively movable with respect to said connection toward and from the work surface; means between said connection and said holder adapted to resist movements of the holder relative to said connection in directions toward and from the work surface; said means being constructed to offer a sufficient degree of resistance to movement of said holder away from the work surface during oscillation thereof toward the work surface to cause the marking tool to forcefully strike against the work surface; and said means being so constructed and arranged as to resist with a lesser degree of resistance movements of said holder in a direction toward the work surface during oscillation thereof in a direction away from the work surface, than the degree of resistance offered by said means to movement of the holder away from the work surface.
